ATOMIZER

Frank E. Brown, Burbank, Calif., assignor to
Frederick M. Turnbull, Los Angeles, Calif.

Application March 10, 1951, Serial No. 14,458

Term of patent 14 years

(Cl. D83—1)

To all whom it may concern:

Be it known that I, Frank E. Brown, a citizen of the United States, residing at Burbank, in the county of Los Angeles and State of California, have invented a new, original, and ornamental Design for an Atomizer, of which the following is a specification, reference being had to the accompanying drawing, forming part thereof, in which:

Fig. 1 is an elevational view of an atomizer, showing my new design;

Fig. 2 is a side elevational view thereof as it appears with the cover removed;

Fig. 3 is a front elevational view of the atomizer shown in Fig. 2;

Fig. 4 is a rear elevational view thereof.

Fig. 5 is a top plan view; and

Fig. 6 is a bottom plan view thereof.

I claim:

The ornamental design for an atomizer, substantially as shown.

FRANK E. BROWN.
